(57) **CLAIM**

(***) Term: **14 Years**

The ornamental design for webcam with a user-configurable shell, as shown and described.

(21) Appl. No.: **29/239,674**

DESCRIPTION

(22) Filed: **Sep. 30, 2005**

FIG. 1 is a perspective view of a webcam with a user-configurable shell showing our new design;

(51) **LOC (8) Cl. 16-01**

FIG. 2 is an exploded perspective view thereof;

(52) **U.S. Cl. D16/203**

FIG. 3 is a front elevational view thereof;

(58) **Field of Classification Search .....** D16/200–204,

D16/208, 218, 225; 348/143, 373, 374–376;

396/427, 535, 536–541

FIG. 4 is a rear elevational view thereof;

See application file for complete search history.

FIG. 5 is a left elevational view thereof;

(56) **References Cited**

FIG. 6 is a right elevational view thereof;

U.S. PATENT DOCUMENTS

FIG. 7 is a top plan view thereof; and,

D349,911 S * 8/1994 Shimizu et al. D16/203

FIG. 8 is a bottom plan view thereof.

D395,056 S * 6/1998 Delaey D16/203

The broken line showing of a cord is included for the purpose of illustrating only and forms no part of the claimed design.
